vale, Pa., a corporation of Pennsylvania

Original application August 27, 1931, Serial No.
559,671, now Patent No. 2,111,352, dated March
15, 1938. Divided and this application March
15, 1938, Serial No. 196,012

7 Claims. (Cl. 177—353)

This invention relates to improvements in train dispatching systems, and more particularly to an improved communication arrangement between the control station and the substations connected therewith.

This application is a division of our copending application Serial No. 559,671, filed August 27, 1931, now Patent No. 2,111,352, granted March 15, 1938, for Train dispatching systems.

10 In the train dispatching system to which the present invention is applied, a control station is connected through a single circuit with a plurality of substations in such a manner that by means of suitable units, train signaling, track switching, and other traffic regulating operations and the like, may be performed at any one of the substations in accordance with instructions transmitted from the control station. The control station is also apprised of the track and 15 roadside signal conditions by means of so-called OS indications, i. e., by means of impulses generated at the control station and affecting indicators thereat, but modified by the condition of the traffic regulating devices at the substations.

20 The communication is by coded impulses directing a substation to perform certain operations or, at the will of the control station operator, informing the latter whether instructions have been carried out at a particular substation. Thus, the control station automatically and periodically tests traffic regulating conditions at all the substations, i. e., obtains information on the positions of track switches, semaphores, track relays, etc.

25

30 If it is desired to effect changes at a substation, the operator at the control station adjusts an impulse transmitter to send code symbols typical for the desired substation and the operations to be performed thereat. A receiver is provided at each substation but only the receiver of the desired substation shall respond and actuate the associated control units in accordance with the code symbols. For the sake of economy and rapidity of communication, the 35 stations are interconnected by a single circuit over which time channels are established through which various stages of the communicating are performed. A definition of this term is given at the end of this specification.

40 The time channels are used also for the purpose of conveying report signals to the control station. The traffic governing devices at the substations are associated with the control circuit over certain channels to actuate receivers 45 at the control station in accordance with code

impulses that have originated at the control station. Over the same channel both control and report symbols may be sent. The faithful cooperation of the control station and substation equipments is insured by synchronously establishing the channels through which the communication takes place and making effective only those substation channels through which it should take place.

5 It will be obvious to those skilled in the art that the present invention may be modified in many respects without exceeding the scope of the appended claims. The dial and distributing switches may be provided with contacts that 10 cooperate with each other in response to other than rotary motions. In fact, any electromechanical circuit switching arrangement may answer the purpose. The expressions "dial switches," "distributor switches" and the like, were arbitrarily chosen and are intended to apply to any 15 circuit switching device suitable for the purpose. Similarly, the connections to the brushes and stationary contacts of the switches and distributors may be reversed; the lamps, polarized relays and the like replaced by other suitable devices, 20 etc. In the systems herein described, direct current is used for certain, and alternating current for other, phases of the communicating and control operations. This also may be modified and varied to suit particular operating requirements. 25 The synchronizing arrangements may be replaced by other arrangements which will insure the timely cooperation between the control station and the substations. The rail switches, track relays and semaphores, which are defined 30 as traffic governing devices, may be altered or supplemented by other traffic governing or testing devices, etc.

35 These and other departures from the specific exemplification of the invention will be apparent 40 to those who may wish to employ the characteristic features of the invention. Most of these features are applicable to train dispatching systems of widely varying character and need not be employed in totality.

45 These and other features are diagrammatically illustrated in the accompanying drawing, only those parts of a train dispatching system being shown which are necessary for explaining to one skilled in the art one manner in which the invention may be practiced.

50 Referring to the accompanying drawing, Figs. 1A and 1B, taken together, illustrate one form of apparatus embodying our invention. Fig. 1A shows apparatus which is located at the control 55

5 office from which all other units are controlled and to which their positions are automatically reported, while Fig. 1B shows apparatus located at one of a plurality of substations scattered along the railway route to interpret symbols transmitted from the central station and control adjoining groups of controlled or operating units, and to transmit to the control station reports indicating the actual positions of controlled units.

10 9 is a control channel which, in the present example, is constituted by a line circuit connecting the central station to all substations. It is grounded at its far end. 54 and 44 are grounded batteries at the central station which supply the energy for control and report symbols, respectively.

15

As will hereinafter be explained, the office apparatus of Fig. 1A is arranged for the control of apparatus at a plurality of field stations, for example, twelve, each similar to Fig. 1B, and it is to be understood that the office apparatus also includes an operator's control board such as is shown in Fig. 1 of our Patent No. 2,111,352, which comprises a plurality of similar sections, or sub-station control panels, one for each station, on which are localized the control and indicating units for the substations.

At each substation there is a track relay 16, to indicate whether an adjoining track section is clear or occupied, and, as shown in the above mentioned patent, at the top of each central station section there is an indicating lamp similar to lamp 49 to indicate the position of the corresponding track relay. The track indicating lamps are not shown herein, but it is to be understood that they are located in sections of a track diagram to show visually the relation of the section indicated to the actual tracks.

40 The apparatus at each substation, as shown in Fig. 1B, may include a group of semaphore signals 47, which may be controlled by the apparatus of our invention to indicate clear for an east-bound or westbound train movement, or to indicate stop. In the corresponding sections of the 45 central station are control levers 53, of which for simplicity but one is shown in Fig. 1A, each having three operating positions corresponding to the three positions of the semaphores or roadside signals; and associated with each lever 53 are three indicating lamps, 49, 50 and 51, one of 50 which is lighted to indicate the position actually occupied by the semaphore.

The apparatus at each substation may also be arranged for the control of a switch machine 13 for operating a track switch, and for each controlled track switch the office apparatus includes a switch lever 55, each operable to two positions "normal" and "reversed". Associated with each switch lever are three indicating lamps, not shown, but similar to the lamps 49, 50 and 51. The left- and right-hand switch indicating lamps, respectively, indicate that the track switch is closed and locked in its normal or reversed position. The middle lamp indicates that the track switch is open or unlocked, which may mean that it is in the process of throwing over or that it has failed to complete its stroke and lock up ready for the passage of a train.

In addition to the units 16, 17 and 18, there may be also other traffic regulating or indicating devices associated with the substations. The single control wire 9 with ground return as shown (or with metallic return), is sufficient for transmitting all necessary control and report symbols between the central station and the substations.

The apparatus normally operates automatically and continuously to receive report symbols from each station in turn in recurrent cycles, in which case the manual switches 35, 34, 40 and 56 occupy their left-hand position as shown, these switches being thrown to the right when it is desired to transmit control signals or symbols to change the position of one or more of the controlled units at a station. 5

At each substation is shown a local battery 19 10 to furnish power for operating the track switches, railway signals and reporting mechanisms, subject to control symbols transmitted over the line circuit 9.

One section of the operator's control board is thus adapted entirely to control a typical group of railway traffic regulating or indicating units comprising one track switch (or group of switches working simultaneously), and one roadside signal or group of signals, and also adapted for receiving reports which indicate one of three conditions for each. In addition, it is adapted to receive reports indicating the position of one track relay. Part of these units may be omitted, or other units up to the equivalent of the units associated with the typical section may be included. 15 20 25

Referring to Fig. 1A, 6 is a motor at the central station receiving power from battery 7 and driving a shaft 20 continuously. 8 designates a 30 governor mounted on the shaft comprising centrifugal brake shoes 5 revolving within a stationary ring 11. At a predetermined speed the brake shoes are thrown into frictional engagement with the ring 11 by centrifugal force and further increase of speed is thereby precluded. By this means shaft 20 is driven at accurately constant speed (for example, one revolution per 0.2 second). 35

40
45
50

Mounted upon the shaft 20 and insulated therefrom are six dial switches 21, 22, 23, 24, 25, 26, each consisting of a revolving brush arm z and a group of nine contact segments or spaces lettered a to i , respectively. A cam 27 also mounted upon the shaft 20 controls a follower 28 spring-biased toward the cam. The follower controls a pawl 29 which actuates a twelve-tooth ratchet 31 in such a manner that the latter advances one step at the end of each revolution of the shaft 20, that is, while the brush arms z are advancing from position i to position a , and completes one revolution or cycle in twelve steps. The dial switches 21—26 perform one complete revolution upon each revolution of the shaft 20, or twelve revolutions per cycle of ratchet 31.

of nine other switches, not shown, but similar to 24, 25 and 26.

Each position I, II, III, etc. of distributor 33 on shaft 30 and the associated dial switch 24, 25, 26, etc. on shaft 20 is assigned to a different station, and each of the positions *a* to *i*, inclusive, of shaft 20 is assigned to a different code step. Each code therefore comprises nine steps corresponding to one revolution of shaft 20, and the recurrent cycle during which connections are established to each of twelve stations in turn corresponds to one revolution of shaft 30.

Referring now to Fig. 1B 66, 67, 60 and 68, respectively, are a motor, a battery, a shaft, and a governor, similar to the parts 6, 7, 20 and 8 already described, but located at a substation along the railway. 63 designates a sleeve mounted upon the shaft 60 and driven thereby through friction. Upon this sleeve are mounted the insulated movable contact or brush arm of a distributor switch 61 and a single tooth ratchet 62. Switch 61 has nine positions in which contact segments *a* to *i*, respectively, are closed. In position *a*, ratchet 62 is engaged by a detent 65, which may be disengaged by the energizing of a magnet winding 69. A spring-biased pawl 76 also engages ratchet 62 and is so located as to stop the rotation of switch 61 with its brush arm in engagement with contact *e*, until pawl 76 becomes disengaged by the energization of a magnet 77.

Each of the switches 21 to 26 is shown for illustration with groups of equally spaced stationary contact segments *a* to *d* and *e* to *i*, with larger spaces between segments *d* and *e* and between segments *i* and *a*. The distributor switch 61 is shown with the nine stationary contact segments all symmetrically spaced. In practice, all of these dial switches may have a larger number of stationary contact groups as may be required. The governors 8 and 68 are so adjusted that the brush arms they control will advance from the first segment *a* to segment *d*, or from the fifth segment *e* to segment *i*, in approximately equal time, but owing to the increased space following segments *d* and *i* on switches 21 to 26, they will be somewhat later in returning to the starting point *e* or *a* than distributor 61, or at least in no case, even with the maximum deviations from normal speed, will the latter arrive at the starting point later than the former.

Segments *a* of the dial switches 24, 25, 26, etc. are permanently connected to the positive terminal of battery 54, and serve to start all substation dial switches simultaneously for each revolution.

On the first step of each code, that is, when the dial switches at the office and stations have their arms *z* in contact with segment *a*, a positive impulse is delivered to the line over a circuit which may be traced from the positive terminal of battery 54, contact *a* and arm *z* of dial switch 24, 25 or 26, contact I, II or III and brush arm *z* of the distributor switch 33, segment *a*—*f* and arm *z* of dial switch 23, switch 40, line 9 to the first station, thence over arm *z* and contact *a* of dial switch 61, through the relay windings 115 and 116 and magnet 69 to line 9 leading to the next station, and so on through each station in turn to ground, thence back to the mid-point of battery 54. Magnets 69 at all stations being thereby energized, each ratchet 75 62 is released by its pawl 65, and all the dial

switches 61 start in unison with switches 21 to 26.

As already mentioned, the switch arms at the office and stations pass over segments *b*, *c* and *d* at approximately the same speed. These segments are used to transmit over the line during each revolution a distinctive symbol calling only that substation required to respond during that revolution, the symbol consisting of positive or negative current on two of the three channels *b*, *c* and *d*.

At each of the dials 24 to 26, two of the three segments *b*, *c* and *d* are connected to the positive or negative terminal of battery 54, while the third is dead. The combination of positive, negative and dead segments on each dial is peculiar to that dial only and constitutes a calling code for one substation which is arranged to respond only to signals transmitted by that particular dial. While I have shown only three dials, 24, 25 and 26, each arranged to call one substation, it should be noted that additional dials, with corresponding segments on the dials 31 to 33, may be provided for any required number of substations. The three segments *b*, *c* and *d* assigned for calling codes will suffice for twelve distinct codes, viz: codes involving three choices of one dead channel and four combinations of polarity on the remaining two segments.

At the substations, these calling and selecting symbols are given effect by the operation of two double wound polar relays biased to remain in their last operated position, having restoring coils 115 and 116 and operating coils 118 and 119, as shown in Fig. 1B. On the first step of each code, the positive impulse transmitted over segments *a* energizes winding 115 in such a direction as to cause contact 121 to move to the left while winding 116 is energized in the opposite direction to cause contact 120 to move to the right, so that the circuit controlled by these contacts is opened at two points at the beginning of each code. The operating coils 118 and 119 are connected in accordance with the station call to two of the segments *b*, *c* and *d*; that is, in the case shown, to segments *b* and *c* and to the outgoing section of the control line 9, in such a direction that a positive impulse over segment *b* is required to operate contact 121 to the right, and a negative impulse over segment *c* is required to operate contact 120 to the left. It will be assumed that the station shown in Fig. 1B is the one corresponding to position I of distributor 33; accordingly in Fig. 1A segments *b* and *c* of dial switch 24 are connected to the positive and negative terminals of battery 54, respectively.

During one particular revolution, the contacts 120 and 121, when closed as described, establish and maintain, during that revolution only, a local circuit from grounded battery 19 to a polar relay contact 123 controlled by a coil 122 which is connected in series with the control line 9 when a channel is established over the segments *f* of dial switches 24 and 61. If positive current is received during the sixth step, contact 123 is operated to the left, completing a local circuit through neutral relay 124 to ground, to set up circuits for receiving control symbols during the remainder of the revolution. If negative current is received during the sixth step, contact 123 is operated to the right, as shown, and completes a local circuit through neutral relay 125, which sets up circuits 75

for transmitting report symbols on succeeding steps.

The fifth step of each code is employed for synchronizing purposes, to insure that a substation dial switch 61, will get into step with the dial switches 21 to 26 even if thrown out of step. On the fifth step, an alternating current impulse is transmitted from the grounded alternator 113 over segment *e* of switch 24, 25 or 26, segment I, II or III of switch 33 to the control line 9 and thence over arm *z* and segment *e* of dial switch 61 and the primary winding of a transformer 114 at each station, to ground.

As already mentioned, a magnet 77 is provided to release the pawl 76 when arm *z* of dial switch 61 is on segment *e*, and the segments are so spaced that arm *z* of dial switch 61 will make contact at segment *e* somewhat before the corresponding contact is closed at switch 24, 25 or 26. Magnet 77 is connected through a condenser 117 to the secondary of transformer 114, the circuit being tuned to respond selectively to the frequency of alternator 113. When the office dial switches arrive at step *e*, current will be induced in the secondary of transformer 114 to cause the magnet 77 to release the pawl 76, ratchet 62 being so positioned as to permit arm *z* of dial switch 61 to start exactly in step with the arms *z* of the office dial switches.

Even if distributor 61 is entirely out of step, as for example, when the system is first started in operation with the dial switches in random positions, it will revolve to segment *e* at some time within its first revolution. There it will be held by its pawl 76 until it is released by current to which the magnet 77 is responsive. This can occur only when the line is connected over a segment *e* at the office to the alternator 113, since current of the required character is supplied over no other segment. Hence, even under the condition assumed dial switch 61 will start its second revolution in step with switches 21 to 26.

When arm *z* of dial switch 61 as released by magnet 77 has advanced until arm *z* makes contact with segment *a*, it will be stopped again by engagement of the ratchet 62 with the pawl 65. A moment later the office dial switch will connect the line through its segment *a* to the positive terminal of battery 54 as already described, to again release arm *z* of dial switch 61 exactly in step with the arms *z* of the office distributors, by the energization of magnet 69.

The second starting pawl 65 serves to correct any variation from synchronism which may have occurred during approximately one-half revolution, but is not capable of bringing the commutators into step from a random position as may be done by the pawl 76, for the reason that magnet 69 is responsive to direct current, whether the current originated at segment *a* or at any other segment.

The sixth step of each code is employed to effect a manual selection to cause the transmission either of report symbols or of control symbols during the succeeding steps of each code.

The segments *f* of dial switches 24—26 are connected through manual selector switch 56 either to the negative terminal of battery 54, with the mechanically interlocked switches 35, 34, 40 and 56 to the left, as shown or to the positive terminal, with these switches to the right. The former connection effects the transmission of a negative impulse to the line to es-

tablish reporting loop circuits at the called substation by energizing relay 125, as already described, and also establishes connections to control indicating lamps such as 49, 50 and 51 at the office. The latter connection effects the transmission of a positive impulse to the line and conditions the office apparatus for transmitting control symbols in accordance with the positions of the control handles 53 and 55, and by energizing relay 124 conditions the selected station to receive these control symbols to effect the operation of the controlled units.

If it is desired to transmit one or more control symbols immediately, without awaiting the moment in the automatic cycle when the controlled unit in question would be connected to the corresponding office lever, the shaft 30 carrying the distributor dials 31 to 33 may be advanced manually to the position corresponding to the unit to be controlled, where it will remain during one revolution of the shaft 20. The dial selected by the distributor 33 will transmit the calling code for the desired substation and establish the necessary local channels for exchanging report or control symbols.

Assuming the manually operable switches 35, 34, 40 and 56 to be to the left, as shown, the seventh, eighth and ninth steps provide three report signals for indicating the condition of the signals, track switch and track section at the selected station. The manually operable switch 40 in its left-hand position connects the line at will to the brush arm of dial 23 (as shown), while in its right-hand position it connects the line directly to the segment *a*, *f* of the same dial, and thence to the brush arm of dial 33. At the instant illustrated, and the position illustrated for switch 40, the line 9 is connected through segment *g*, *i* of dial 23 through neutral relay coil 41 and polar relay coil 42, to the positive pole of battery 44, and thence to ground. The battery is also connected through a coil 43 opposed to the coil 42, and through an artificial line or resistor 45 to ground. At the instant illustrated, that is, with the brush arms on segments *g*, the line 9 is connected to ground through a loop circuit associated with one controlled unit (at a substation), this loop having three conditions, each indicating one state of a controlled unit (e. g., a semaphore) at this substation, viz: closed through low resistance, closed through high resistance, and open circuit.

Assuming the station of Fig. 1B to have been selected so that relay 125 is energized, this circuit may be traced from the incoming line wire 9 over brush arm *z* and segment *g* of dial switch 61, a back contact of relay 124, switch 135, resistor 136 to the outgoing line wire 9; while at each non-selected station the circuit extends from the incoming line wire 9 over brush arm *z* and segment *g* of dial switch 61 and back contacts of relays 124 and 125 in series to the outgoing line 9, and thence to ground at the end station. In the case illustrated, assume the loop circuit at the selected station to be connected into line 9 as in the first condition; current passing from battery 44 through relay coils 42 and 41 to the line is a maximum. The resistor 45 is so adjusted that the magnetizing force exerted by the coil 42 under this condition exceeds that exerted by the constant current passing through coil 43 to the resistor; and the right-hand contact of the polar relay 43 will be closed. The front contact of the neutral relay 41 will also be closed.

The high resistance in the second condition of

the loop circuit is so chosen that it will reduce the magnetizing force, due to line current through the coil 42, to a value less than that in coil 43, with the result that the left-hand contact of the 5 polar relay will close, but the neutral relay 41 will still be energized sufficiently to close its front contact. However, if the line circuit is broken at the substation loop, the polar relay will close its left-hand contact, and the back contact of 10 the neutral relay will remain closed.

It will be observed that the resistor 45 connected to the polar relay coil 43 corresponds in part with the artificial line or balancing network employed in certain duplex telegraph systems, but differs in that it is not required to balance the line characteristics but merely to produce an effect less than that of the normal line impedance and greater than the line impedance when the latter has been increased to several 20 times its normal value. For this reason a plain resistance as shown, traversed by a constant current, will ordinarily suffice. However, in cases where exceptional line constants make it desirable, the resistor may be replaced by any well-known type of artificial line, as indicated at 45 in Fig. 7 of our Patent No. 2,111,352, and the battery current may then be cut off at each step and reapplied simultaneously to both windings 42 and 43, by the provision of another dial switch 30 on shaft 20 as explained in the patent.

Referring now to the circuits controlled by the line relays 41 and 42, it will be seen that the front contact of the neutral relay 41 and the right-hand contact of the polar relay 42 are connected to the positive pole of battery 52 and the back contact of relay 41 and the left-hand contact of relay 42 are connected to the negative pole, the midpoint of the battery being grounded. At the instant illustrated, the contact of the 40 polar relay is connected over switch 35 through brush arm *z* and segment *g* of dial switch 21, through coil of polar relay 46 and through segment I and brush arm *z* of distributor dial 31, to ground. The polar relay 46 is designed to 45 have a substantial bias toward its last operated position, so that either contact when closed remains closed until reversed by reversal of current in the operating coil. So long as the circuit just described is maintained, the relay 46 closes its left-hand contact if the right-hand contact of relay 42 is closed, and closes its right-hand contact if the left-hand contact of relay 42 is closed. If the operating circuit through 50 46 is then interrupted, its contact remains closed 55 at the last operated position until the operating circuit is reestablished with the contact of relay 42 in the opposite position.

In like manner, the contact of relay 41 is connected over switch 34 through the brush arm and 60 the segment *g* of dial switch 22, through the coil of polar relay 47 and through segment I and brush arm *z* of distributor 32 to ground. At the instant illustrated, when the dials 21 and 22 are closed through segments *g*—*g* and the distributor dials 31 and 32 are closed through segments 65 I, I, the polar relays 46 and 47 thus assume positions which are determined by the positions (at that instant) of relays 42 and 41. When the distributor and dial switch arms have moved on 70 to other segments, the relays 46 and 47 maintain their operated positions until the next occasion when their operating circuits are closed through segments *g*—*g* and I—I.

The moving contact of relay 47 is connected 75 to the positive pole of battery 48, the negative

pole being grounded. The right-hand stationary contact is connected through an indicating lamp 49 to ground. The left-hand contact is connected to the moving contact of the relay 46 and thence, according to the position of the latter, either through the right-hand contact and indicating lamp 50 to ground, or through the left-hand contact and indicating lamp 51, to ground. Since the relays 46 and 47 repeat the positions of relays 42 and 41, and since the latter are dependent on the resistance of the loop circuit which is connected at that instant in the line, the indicating lamps 49, 50 and 51 indicate the connection (or absence of connection) through the loop circuit at the instant when connections are established as described; if the loop circuit is open, neutral relay 41 will be down and indicating lamp 49 will light; if the loop circuit is closed through high resistance 136, relay 41 will be up and relay 42 to the left, under 20 which condition indicating lamp 50 will light; if the loop circuit is closed through low resistance, relay 41 will be up and relay 42 to the right, and indicating lamp 51 will light. Furthermore, after the operating circuit through the 25 coils of relays 46 and 47 has been interrupted at the distributor dials 21, 22, the lighted lamp will continue to burn until the operating circuit is reestablished, at which time the resistance of the substation loop circuit will again determine 30 which of the three indicating lamps shall light.

As described, the indicating lamps 49, 50 and 51 are controlled by operating circuits extending from the segments I—I of distributor dials 31 and 32 to segments *g*—*g* of dial switches 21, 22. 35 Similar circuits may extend from the segments I—I through other pairs of relays similar to 46 and 47, which are controlled over segments *h*—*h* and *i*—*i* of dial switches 21 and 22 in accordance with the positions of the contacts of relays 41 40 and 42 on the eighth and ninth steps of the code, to control other groups of lamps similar to 49, 50 and 51. At the end of one revolution of the brush arms of dial switches 21 and 22 the brush arms *z* of distributors 31 and 32 will advance to 45 segments II—II. From these segments three other pairs of operating circuits, controlling three other groups of indicating lamps, may extend to the segments *g*—*g* to *i*—*i* of distributor dials 21 and 22. Three other groups of indicating lamps may be controlled by circuits terminating on the segments III, III of distributor dials 31 and 32, so that we may have in all three 50 times three, or nine groups of indicating lamps controlled by the line circuit 9 successively as 55 the distributor brush arms revolve. If nine substation loop circuits are successively connected in the line, each group of the nine groups of indicating lamps will indicate the condition of the corresponding substation loop circuit when last 60 connected, thereby indicating the position of the corresponding operating unit which controls the loop circuit. In the case of operating units having only two positions, such as track relays, the high resistance connection at the loop circuit 65 may be omitted, together with relay 46 and indicating lamps 50 and 51. The two required indications will then be produced by open and closed conditions of relay 47, resulting in dark and light 70 indications at the lamp 49.

Instead of receiving reports to indicate the position of operating units at the substations, it may be desired to transmit control signals or symbols to change the position of one or more controllable operating units. The manual 75

switches 34, 35, 40 and 56 will then be thrown to the right. Switches 34 and 35 will open the control circuits for all indicating lamps. Switch 56 will be instrumental in transmitting a symbol 5 to render the desired substation receptive to control symbols, as hereinbefore described, and switch 40 will connect the line 9 through segment *af* in all positions of distributor dial 23 to the brush arm *a* of distributor 33. At the instant illustrated, line 9 will be connected through segment *af* of dial 23 and segment I of dial 33 to the brush arm of distributor dial 24, and thence over segment *g* to the upper blade of three-position control switch 53. When the brush arm of distributor dial 24 advances to segment *h*, the circuit will be transferred to the lower blade of control switch 53. Thus in the two successive time channels in which the brush arm of dial 24 makes contact at *g* and *h*, respectively, the control line 10 is connected first to the upper and then to the lower blade of manual switch 53. According to the position of the latter, line 9 is connected to the positive or negative pole of battery 54 or to neither in the following order:

- 25   Upper position: Neither—negative;
         Middle position: Negative—positive;
         Lower position: Positive—positive.

The receiving elements at a substation are arranged to respond selectively to these three combinations of current during two time channels, establishing a distinctive roadside signal or semaphore indication in response to each combination.

Similarly, segment *i* of dial 24 may be connected through manual switch 55 to the positive or negative pole of battery 54, and transmits a positive or negative current impulse over the control line to select one of two possible operations of another controlled unit at a substation. 35 Similar branch circuits, including other control switches, may extend from segments *g*, *h* and *i* of dials 25 and 26. During three successive revolutions, as the dials 24, 25 and 26 are connected successively to the line through dial 33, nine control channels will be established. One two-position operating unit, such as a track switch, may be controlled over any one of these channels; any three-position unit, such as a group of roadside signals, requires to be controlled over two 45 such channels.

It has already been explained that on the sixth step of the code contact 123 of relay 122 is positioned to pick up neutral relay 125 or 124 at the selected station, depending upon whether report or control symbols are to be transmitted on 55 succeeding steps. It will be seen from the drawing that when relay 124 or 125 is energized, the opening of its back contacts causes the line current to pass through loop circuits in series with the control line 9 over segments *g*, *h* and *i* of dial switch 61 during successive operating stages of the distributor either to receive control symbols or characteristically to affect report symbols, 60 viz: from segment *i* through polar relay coil 126 or through report switch 132 to the outgoing portion of control line 9; from segment *h* through polar relay coil 128 or report switch 133 to the same point; and from segment *g* through polar relay coil 130 or report switch 135 to the same point. Assuming switches 35, 34, 40 and 56 to be to the right, relay 124 will be energized and relay 125 deenergized; the back contacts relay 70 75 124 are therefore open and current through the loop circuits must traverse the coils of relays

126, 128 and 130. Report switches 132, 133 and 135 are bridged by back contacts of relay 125 which are therefore at this time short-circuited and ineffective.

Line current through the channels *g*, *h* and *i*, 5 respectively, traverses the relay coils 130, 128 and 126, and determines the positions which their respective contact fingers 131, 129 and 127 will assume, and which (by virtue of inherent bias toward their operated positions) they will maintain until reversed by opposite current in their operating coils. Thus the position of the contact fingers 131, 129 and 127 is determined by the polarity of line current through the corresponding channels *g*, *h* and *i* in that revolution of dial 61 after relay 124 has been energized as described in response to the transmission of the calling symbol for this substation. The coils 126, 128 and 130 are connected to close their respective contact fingers to the right when the current 10 through them is positive, and to the left when negative. Thus when relay 126 is actuated by positive current, contact 127 moves to the right, connecting the local battery 19 to the "reverse" 15 operating circuit 138 for the track switch. As 20 shown negative current has been last received in channel *i*, and finger 127 is to the left, energizing the "normal" track switch operating circuit 137.

When operating coil 128 receives negative current over channel *h* from the lower blade of control switch 53 it operates its contact finger 129 to the left, energizing local control wire 139 to set up roadside signals for eastbound traffic. This occurs irrespective of the position of finger 131; but when finger 129 is closed to the right by positive current in its operating coil, it interrupts the circuit to the eastbound wire and connects the battery 19 to contact finger 131. The position of the latter, according as positive or negative current flowed through coil 130 during channel *g*, determines whether battery will now go on local wire 141 that sets the roadside signals for westbound traffic, or on local wire 140 that sets them to "stop."

Response to control symbols over channels *g*, *h* and *i*, as just described, was dependent upon the previous receipt of positive current through manual switch 56 and channel *f*, causing contact finger 123 to close at the left and energize 50 relay 124. When the manual switch 56 is closed to the left, as shown, negative current will flow in channel *f*, and contact finger 123 will close at the right and energize relay 125. The relay coils 126, 128 and 130 will then be short-circuited by 55 contacts of the deenergized relay 124 and therefore rendered ineffective; but the contacts of relay 126 will be open and the impulses sent during channels *g*, *h* and *i*, respectively, will be characteristically affected by the positions of report switches 132, 133 and 135. Report switch 132 may be, for example, a contact of a track relay 16 used to indicate whether a track circuit is 60 clear or occupied. When open, as shown, it will cause an indicating lamp such as 49 in Fig. 6 65 (but controlled over channel *i*) to light. When closed, it will cause the lamp to be extinguished.

Report switch 133 may be actuated by the mechanism of a track switch operating machine, and when closed through the line resistance only, 70 as shown, it may indicate that the track switch is closed and locked in its normal position. An indicating lamp similar to 51 will then be caused to light. When closed through high resistance 134 it may indicate that the track switch is un- 75

locked. An indicating lamp similar to 50 will light. When open it may indicate that the track switch is closed and locked in its reverse position and may cause the indicating lamp corresponding to 49 to light.

In like manner the report switch 135 may be actuated by a roadside signal mechanism, or equivalent circuits may be closed through relays associated with the roadside signals, and the 10 three resulting conditions in the loop circuit, viz: open, closed through high resistance, and closed through normal line resistance may control the set of indicating lamps associated with channel *g* at the central station. The three indicating 15 lamps associated with channel *g* and report switch 135 may indicate, respectively, that the signals are set up for eastbound traffic, set up for westbound traffic and set at stop.

In resume, using dial switches of only nine 20 positions on shaft 20 and of twelve positions on shaft 30, as shown in the drawing, there could be handled twelve substations (three shown), "central" being able at each to control one track switch (or group of such) to two positions and 25 one roadside signal (or group of such) to three positions; central also receiving continuously from each in succession (except when sending control symbols or codes), automatic reports about one track switch (or group) having three 30 conditions, about one roadside signal (or group) having three conditions, and about one track relay having two conditions.

Nine time channels to each substation, set up by the synchronous operation at "central" and 35 at substations of nine-position revolving dial switches, are shown utilized as follows:

Positive on channel *a* starts off all substation dials in step with central. (Fig. 1B, magnet 69 and detent 65). Substation dials gain slightly 40 on central, so will be already stopped, and will start each cycle exactly with "central." This impulse on *a* also restores to normal or open contact condition (wiping out the influence of past 45 codes), the two code receiving polar relays at all substations (120 and 121, Fig. 1B). It is by the twelve possible combinations of polarities in each of these two relays with their connections to the three time channels *b*, *c*, *d*, that each substation 50 is differentiated from the others and is adapted to answer just one of the twelve symbols or codes.

Positive and/or negative impulses on channels *b*, *c*, *d*, constitute the substation selecting symbols or codes. Each one of these (twelve possible) is determined by the positive or negative 55 battery connections on two out of the *a*, *b*, *c*, segments of dials 24, 25, etc.

Alternating current on channel *e* puts all substations in synchronism with central, even if 60 badly displaced.

Positive or negative goes out on channel *f*, according to the right or left position of manual switch 56, and this choice determines whether the impulses to be sent on channels *g*, *h*, *i*, shall cause 65 movement of roadside signals, track switches, or the like, or shall light indicating lamps at central to report conditions of the track switch, track relay, semaphore or the like.

Channels *g*, *h*, when manual switch 56 is in the 70 right-hand or "control" position, carry the codes that actually determine motion of roadside signals at the selected substation. As illustrated, only three codes are sent on *g*, *h* (eight are possible, using either of two polarities on either or both of two channels). More are not needed to

control roadside signal conditions and would complicate substation receiving arrangements.

Channel *i*, with manual switch 56 in right-hand control position, carries a two-unit code (positive or negative) to set the track switch to 5 reverse or normal.

Channels *g*, *h*, *i*, when manual switch 56 is in left-hand or "report" position, carry no codes but are used as mere individual channels for connecting a battery at "central" to individual substation loops, each associated with a track switch, a roadside signal, or a track relay, during which connections these three loop impedances are compared, individually, to an artificial line at central and their conditions individually recorded at central on lamps.

In many aspects the various features of the present invention are applicable to all types of train dispatching systems, and particularly to those in which devices at the control station and 20 substations are operated in synchronism. As generally used, the word "synchronism" is applicable both to independently and dependently timed devices; in other words, two devices may be said to operate in synchronism where they are 25 driven by two independent but identical clockworks, and they may be said to operate in synchronism also where one device is operated by a clockwork and causes the operation of the second device in step-by-step or in continuous correspondence to its own operation. In accordance with one of the features of our invention, devices such as distributors at the control station and at the substations, are independently timed and operated, the only timing connection between 30 the two being a single impulse by means of which the two devices are started off together or stopped together. To distinguish from those systems often called synchronous, in which a one-to-one correspondence of events (such as local line wire 35 connection changes) is produced at distant points by causal means instead of by pure time measurement, we have frequently used the term "time channel" on a certain conductor.

This term, as employed herein, may be defined 40 as a specific conductor or circuit made available for a specific part of a recurring time cycle.

What is claimed is:

1. In a remote control system, a control station and a field station connected by a single line 50 circuit, a plurality of movable devices at said field station, a plurality of indicators at said control station, impulsing means at said control station only for energizing said circuit with a series of code impulses, means effective only when a certain impulse of a series of impulses delivered by said impulsing means is of a given polarity to control said movable devices in accordance with the character of other impulses of said series, and means effective when said certain impulse is of 55 the opposite polarity to control said indicators in accordance with the characters of said other impulses.

2. In a remote control system, a control station and a plurality of field stations connected by 60 a single line circuit, movable devices at said stations, indicators at the control station for indicating the condition of said movable devices, distributors at the control station and at each field station automatically operable through recurrent 65 cycles to transmit indications one at a time over said line circuit from each field station in turn to actuate said indicators, each in accordance with the condition of the corresponding movable device, and manually operable means at the con- 70 75

- tral station for suspending said automatic operation and establishing communication with a selected field station to control the movable devices at such station over said line circuit.
5. 3. In a remote control system, a control station and a field station connected by a single line circuit, means at the control station only for transmitting series of impulses over said line circuit, means at both stations for determining the 10 character of said impulses, and selecting means for causing but one character determining means or the other to be effective during the transmission of any one series of impulses from said control station.
15. 4. In a remote control system, a control station and a field station connected by a single line circuit, means at the control station for transmitting series of impulses over said line circuit, movable levers at said control station, movable devices at said field station, manually operable selecting means in the control station which in one position causes the character of said impulses transmitted from the control station to be determined in accordance with the 20 positions of said levers at the control station and in another position causes the character of said impulses transmitted from the control station to be determined in accordance with the positions of said devices at the field station, a control 25 means at said field station selectively controlled in accordance with the character of said impulses when said selecting means is in said one position, and indication means at said control station selectively controlled in accordance with the 30 character of said impulses when said selecting means is in said another position.
5. In a remote control system, a control station and a field station connected by a single line circuit, code transmitting means at the control 40 station for transmitting a series of impulses of selected polarity over said line circuit, code transmitting means at the field station for governing the character of certain impulses of said series to transmit messages from said field station

to said control station when a particular impulse of said series transmitted from the control station is of one polarity, means at the control station for governing the character of said certain impulses to transmit messages from said control station to said field station when said particular impulse in a series is of the opposite polarity, and manually controlled means at the control station for selecting the polarity of said particular impulse.

6. In a remote control system, a control station and a plurality of field stations connected by a single line circuit, means at the control station for transmitting code signals in one direction over said line circuit comprising a series of impulses of a given relative polarity including selected impulses of the opposite polarity, and means at each field station for transmitting code signals in the other direction over said line circuit comprising means for modifying the strength 15 of selected ones of said impulses.

7. In a remote control system of the selector type; the combination with a control office and a field station; of a single line circuit connecting said control office with said field station; impulses only at said control office for energizing said line circuit with a plurality of impulses; code sending means at said control office and at said field station for determining the character of said impulses except the first; manually operable means selectively determining the character of the first impulse; and means responsive to the character of the first impulse for selectively causing either one or the other of said code sending means to be effective, whereby messages 30 are caused to be transmitted from said control office to said field station or from said field station to said control office dependent upon the condition of said manually operable means.

ELSIE A. BLAKE,
Executrix of the Estate of Eli J. Blake, De-
ceased.
